BAGEL SLICER

Paul P. Blum, Stamford, Conn.
(381 Canal Place, Bronx, N.Y.)

Filed Oct. 14, 1965, Ser. No. 87,477

Term of patent 14 years

(Cl. D44—1)

FIG. 1

FIG. 2

FIG. 3

FIG. 4

FIG. 5

I claim:
The ornamental design for a bagel slicer, as shown.
